WARD B. STORY, OF BROOKLYN, NEW YORK, ASSIGNOR TO WARD B. STORY COMPANY, INC., OF NEW YORK, N. Y., A CORPORATION OF NEW YORK.

SHEET-PILER.

1,252,857.

Specification of Letters Patent. Patented Jan. 8, 1918.

Substitute for application Serial No. 762,784, filed April 22, 1913. This application filed July 7, 1915. Serial No. 38,445.

To all whom it may concern:

Be it known that I, WARD B. STORY, a citizen of the United States, residing in the borough of Brooklyn, county of Kings, city 5 and State of New York, have invented a certain new and useful Sheet-Piler, of which the following is a specification.

This invention relates to devices for receiving sheets, usually from a printing press, and supporting them in a vertical pile, and is a revival of application Serial No. 10 762,784, filed April 22, 1913. It has particular use with the delivery mechanism described in my co-pending application for 15 patent, filed April 22, 1913, Serial No. 762,783, and, in fact, is illustrated herein as attached to such an apparatus, but this construction is shown solely for purposes of illustration, as the present invention 20 is not so limited in use. The objects of the invention are:

First: Keeping the top of the pile at approximately a uniform distance from the delivery belts.

Second: The sheets are deposited without adjusting for different thickness, and without attention from the operator. As the height of the pile increases, the sheets at the lower part are closer together or compressed by the weight of the sheets above, so that a uniform feed is impossible. Pilers at the present time are set approximately for average feed, and the operator sets the feed down or keeps it back at intervals. It 35 requires constant attention.

Third: The machine made according to this invention is automatic, and requires no adjustment and no attention from the operator.

Fourth: To render it possible, when the pile is removed, to return the board support without turning the feeding screws.

Fifth: To make it hand-manipulated, for setting down by hand, so that an incomplete pile can be removed.

These and further objects will more fully appear from the following specification and accompanying drawings, considered together or separately.

In the drawings.

Figure 1 is a side elevation of a printing press equipped with a piler embodying the invention.

Fig. 2 is a plan view of the piler.

Fig. 3 is a section on the line 3—3 of 55 Fig. 2.

Fig. 4 is a section on the line 4—4 of 60 Fig. 2.

Fig. 5 is a section on the line 5—5 of Fig. 4.

Fig. 6 is a side elevation of a nut, the view being taken at right angles to Fig. 4.

Fig. 7 is a section on the line 7—7 of Fig. 3.

Fig. 8 is a section on the line 8—8 of 65 Fig. 2.

Figs. 9 and 10 are detail perspective views of the regulating mechanism.

Fig. 11 is a section on the line 11—11 of 70 Fig. 10.

Fig. 12 is a similar view to Fig. 11, with the parts in a different position; and Fig. 13 is a detail view.

In all of the views, like parts are designated by the same reference characters.

Referring to Fig. 1, the frame 1 carries the usual parts of the press, such as the printing couple, and the transfer cylinders such as are described in my co-pending application for patent filed April 22, 1913, 80 Serial No. 762,783, entitled "Delivery mechanism for printing presses."

On the frame is a continually rotating shaft 2. This shaft operates in timed relation with respect to the feeder. This shaft 85 carries a disk 27^a provided with pins 28^a which coöperate with slots 29^a in a disk 30^a as in my copending application above referred to. This shaft, in the embodiment chosen for illustration, makes one revolution during the period of time that four sheets are fed to the piler. Any mechanism may be employed for feeding the sheets, but I illustrate that which is disclosed in my copending application for patent. The sheets are 90 delivered to the pile *a* by means of grippers *b*, *b*, carried by belts *c*. These belts are actuated by mechanism *d*, which gives the belts an intermittent, fast and slow movement.

The grippers grasp the sheet, and move it 100 to the position immediately over the pile, and then release it. At the moment the grippers release the sheet they are at rest, that is,—the mechanism *d* has brought the belts *c* to rest, so that the sheet has no forward motion. Two grippers are shown: each engages with an alternate sheet. The sheets are delivered to the grippers *b*, *b*, by 105

means of grippers, *f*, *f*, *f*, and by belts *g*. These latter grippers *f*, *f*, *f*, receive the sheets from the transfer cylinder, all in the manner described in my co-pending application above identified.

The shaft 2 has a crank 3, and connected to the crank is a pitman 4. This pitman actuates the mechanism for lowering the board 5 of the piler. This board slides vertically between standards 6, 6, forming, in the embodiment chosen for illustration, a portion of the frame 1. The reciprocation of the pitman 4 actuates devices for feeding the board 5 downward at a speed which depends upon the rate of growth of the pile upon the board, the speed of movement of the board downward being determined by mechanism to be described.

The details of the board are shown in Fig. 2. It is supported upon frames 7, 7, having forked extremities. These extremities have openings 8, (Fig. 6) in which lie projections 9, 9, of triangular cross-section. These projections are attached to nuts 10, which engage with vertical threaded shafts 11. These shafts are four in number, as shown, and lie inside and parallel with the standards 6, 6. The pitch of the threads on all of the shafts being the same, it is apparent that if all of the shafts are rotated at the same rate of speed, the board will be always supported in a horizontal position. The projections are somewhat smaller than the openings, so that there will be some slight lost motion, and the nuts will be free to adjust themselves on the shafts without jamming,—a structure made desirable owing to the nature of the nuts, as will be described.

The means for simultaneously rotating the shafts is as follows, reference being had to Figs. 2 and 4: Each shaft is provided with a gear wheel 12, preferably having inclined teeth, as shown. The gear wheels on the front and back of the apparatus are connected together by cross shafts 13, having gears 14, which mesh with the gears 12. A driving shaft 15, at right angles to the cross shafts, has gears 16 which also mesh with the gears 12, 12, on the front and back shaft at one side, as shown in Fig. 2. It is apparent that upon the shaft 15 being rotated, it will rotate two of the shafts 11 by direct engagement of the gears 16 and 12, and the rotation of these gears 12 will rotate the cross shafts 13, 13, and the other two vertical shafts 11, thus rotating all four of the vertical shafts at the same speed. The shafts 11, 13 and 15, are supported in suitable bearings, as shown. The shaft 15 projects beyond the side of the frame 1, and has attached to it the mechanism for rotating it, such mechanism being actuated by the pitman 4, and being as follows, reference being had to Figs. 7 and 9, the former show-

ing the parts assembled, and the latter showing them separated for greater clearness, the shaft 15 being omitted. The pitman 4 is connected to a lever 17, carried by a sleeve 18, loosely mounted to turn freely upon the shaft 15. The sleeve carries a second lever 19, so that the levers 17 and 19 with the sleeve 18 virtually constitute a single lever or crank, pivoted between its ends, and free to rotate or oscillate upon the shaft 15 without turning the latter, the shaft merely affording a convenient support for the crank. The lever 19 carries a pawl 20, which engages with a ratchet wheel 21, which is carried by the shaft 15, and is so connected to the latter, as by a key, that it will rotate it. This ratchet wheel is shown as having four teeth, but the number is immaterial, so that the pawl 20 will successively engage the teeth as the lever 19 is oscillated by the movement of the pitman 4.

From the foregoing description, it is apparent that the reciprocating movement of the pitman will oscillate the lever 19, and pawl 20, and the latter will necessarily engage with the teeth of the ratchet wheel, rotating the latter, in the embodiment chosen for illustration, in the clockwise direction, and thus rotating the shaft 15, and through the gear wheels and threaded shafts and nuts, will lower the board 5.

The parts are so proportioned that the rate of travel of the board will be faster than is necessary in order to keep the top of the pile at the proper level, no matter how rapidly the depth of the pile grows. This rate of feed is the maximum, and takes into consideration the greatest thickness of sheets that will be fed, and usual accidents and conditions, such as warping of certain sheets, irregularity, etc., which may cause the pile to grow at an abnormally rapid rate, so that the board will always travel downward at a rate of speed greater than the rate of increase of thickness of the pile of sheets, so that the top sheet will never be too high, but, on the contrary, will always become lower as the pile increases in height. In point of fact, the top of the pile is maintained at a constant level owing to devices herein described, which disconnect the feeding mechanism.

The next part of the mechanism to be described will be that for disconnecting the feeding mechanism at intervals, determined in accordance with the height of the pile, so that the top of the latter will be at a constant height. This mechanism which I term the "disconnecting mechanism," is as follows:

It is shown at the right of Figs. 2 and 3, and in Figs. 8, 10, 11 and 12.

A finger 22, is so mounted that it will descend at regular intervals upon the top of

the pile *a* (Fig. 3). If the top of the pile is at the proper height, the disconnecting mechanism will not operate (see Fig. 12), if the top of the pile is too low, (see Fig. 11) the finger will descend below its normal position and disconnect the feed mechanism. The details of the mechanism are as follows: The finger 22 has a rearward extending projection 23. The finger is mounted to turn loosely upon a shaft 24, mounted in suitable bearings. This shaft is adapted to be oscillated (*i. e.*—rotated alternately in opposite directions, for a part of a revolution) by mechanism to be described, and the finger 22 is adapted to be lifted and depressed. The connections between the shaft and the finger are as follows:

The shaft carries a lever 25 (see Figs. 10 and 11). This lever is connected to the projection 23 by means of a rod or link 26. This link has headed extremities, and is loosely mounted in openings in ears 27, 27, on the lever 25 and projection 23. This forms a species of connection which will cause the projection to follow the lever 25 as the latter is moved by the rotation of the shaft. A spiral spring 28 surrounds the link, and abuts against the ears and holds the latter normally separated. By the before-described mechanism it is apparent that as the shaft 24 is rotated in either direction, the finger will be moved with it. The shaft 24 is rotated through about a quarter revolution, to quickly lift the finger clear of descending sheets and hold it elevated, and then quickly depress it upon the top sheet, by the following mechanism: This mechanism is designed to elevate the finger and depress it at intervals depending upon the design and construction of the machine. In the embodiment chosen for illustration, it is elevated and depressed after four sheets are fed to the pile, but it must be understood that the rate of speed of travel of the finger may be varied as desired. In order to not interfere with descending sheets, its movement must be rapid, and must occur during the intervals between the feeding of sheets, and it must remain in elevated position while the sheets are being fed. In other words—with the embodiment of the invention chosen for illustration, the finger must be quickly elevated, and remain elevated while four sheets are being fed, then it must be quickly depressed to engage with the top sheet, then quickly elevated, all before the next sheet is fed, and, of course, the rate of feed of the sheets and the intervals between them cannot be altered, so the movement must be rapid and the finger must remain elevated and in practically immovable position while the sheets are being deposited upon the pile. This mechanism is in detail best shown in Fig. 3, and to the left of Fig. 10. A pitman 29 is con-

nected to the lever 17, and virtually forms a continuation of the pitman 4, and partakes of the same movement. This pitman 29 is connected to a toothed sector 30, rotatably mounted above the shaft 24. It engages with a gear wheel 31, to get the proper direction of rotation; the gear wheel 31 engages with a gear wheel 32, (see Fig. 10). This latter gear wheel carries the anchor member of a Geneva stop motion, such member being formed of a disk 33, with a cut-away portion, and a lever 34, opposite the cutaway portion, and with an offset roller 35. The driven member of the stop motion carries a lever 36, with a slot for the passage of the roller, and a sector 37, for engagement with the disk.

It is apparent that upon the gear 32 being rotated, through the agency of the pitman 29, sector 30, and gear 31, the roller will enter the slot, and swing the lever 36, through the arc of the circle, giving the shaft 24 a quarter turn. After the roller leaves the slot, due to the continued rotation of the gear 32, the sector 37 will engage with the rounded portion of the disk 33, and will lock the shaft 24 immovably in position. The lever 34 is so arranged that it will engage the roller 35 with the slot, at the beginning of movement of the pitman 29, and will leave the slot shortly afterward, and continue its movement during the rest of the travel of the pitman; thus keeping the finger 22 elevated during the greater portion of the movement of the pitman, and causing it to be quickly elevated and quickly depressed.

I will now describe the mechanism which connects the finger 22 and the pawl 20, so that the latter is lifted away from the ratchet wheel, when the top of the pile is at a position below normal.

This mechanism is best shown in Figs. 3, 9, 10 and 11.

Referring to Figs. 10 and 11, it will be noticed that the projection 23 carries a dog 38 loosely pivoted to it. The upper end of the dog carries a roller 39, which is adapted to engage with a fixed cam 40, depending from the frame 1. The other end of the dog is adapted to engage with a lever 41, pivoted to turn upon an axis concentric with the shaft 24. When the roller 39 comes in contact with the cam 40, the lever 41 is released. The projecting end of the lever is adapted to be engaged by the dog when the finger 22 is stopped in its downward passage by the pile, when the finger goes below the normal position (in the examples chosen for illustration slightly above the horizontal position). This position occurs when the top of the pile is at normal. When the top of the pile is below normal, the finger will be arrested by the pile at a lower position, which may be expressed as "below normal." The

dog 38 carries an ear 42, with an opening through which the link 26 loosely passes, and the spring 28 engages with this ear, and normally holds it in engagement with the ear 27 on the projection 23.

When the finger 22 descends to the normal position, as shown in Fig. 12, the dog 38 having been moved out of the path of the lever 41 by the engagement of the roller 39 with the cam 40 on the upward movement of the finger, the end of the dog cannot engage the lever 41 for the reason that the lever 25 and the extension 23 have not been separated to an extent to allow the dog to pass the end of the lever 41, and consequently when the finger is raised the sleeve 43 will not be rotated, the disconnecting mechanism will not be operated and the table feed will continue. It is, therefore, apparent that when the pile is at normal, the disconnecting mechanism is not operated, and the speed of normal feed will soon lower the top of the pile to the position below normal. When the top of the pile is in position below normal, indicating too rapid feed of the board 5, the finger 22 will fall a greater distance than before, see Fig. 11, the lever 25 and extension 23 will be separated to a greater extent, the dog 38 will be raised above the end of the lever 41 and the spring 28 will swing the dog inward so that when the shaft 24 is rotated to raise the finger the extension 23 is depressed, the dog will engage the lever 41, rotate the sleeve 43, and the disconnecting mechanism will be actuated to arrest the driving mechanism of the board, until the top of the pile reaches the normal position. The connection of the lever 41 to the disconnecting mechanism is as follows: The lever 41 is carried upon a sleeve 43, which surrounds and is supported by the shaft 24. This sleeve carries a lever 44, which is connected to and moves a rod 45. This rod 45 is connected to a lever 46, mounted to turn on the hub 47 of the ratchet wheel 21. This lever 46 carries a guard 48, for holding the ratchet mechanism, about to be described, in place. A spring 71 (see Fig. 3) tends to move the rod 45 and lever 46 to the left. The spring 71 is expanded during the operation of raising the finger 22 after it has descended below the normal position and the lever 41 has been engaged by the dog 38. On the lowering of the finger 22 and the raising of the dog 38 the spring 71 will move the lever 44 to the left and raise the lever 41. This movement will continue until the spring is collapsed when the upward movement of the lever 41 will be arrested. A shaft 49, shown in broken lines in Fig. 7, is carried by the lever 19, and supports the pawl 20. A continuation of this shaft supports a bell crank lever 50, which has an opening (see Fig. 9), for engagement with the shaft 49. One limb of

the bell crank lever 50 engages with the spring 51; the other end of the spring engages with a projection 52 on the pawl 20, and tends to depress the latter. A second limb of the bell crank lever carries a roller 53, which engages with a fixed cam 54 mounted on the frame 1. The third limb of the bell crank lever engages with a lever 55, (see Fig. 9), this lever being under the bell crank. One end of the lever 55 has a notch 56, adapted to be engaged by the third limb of the bell crank lever 50. The other end of the lever has a notch 57, adapted to be engaged by a projection 58 on the pawl 20. The lever 55 has a projection engaging in a notch on a ring 59, which loosely turns on the hub 47. The sides of the ring adjacent to the projection on the lever 55 are inclined, as shown, so as to limit the oscillating movement of the lever 55. The ring also carries a projecting roller or pin 60, which lies in the path of the lever 46.

The operation of this portion of the mechanism is as follows:

As before described, when the finger 22 descends to the normal position, the rod 45 is not moved. This is not necessary, as the feeding devices should not be disconnected. When the finger descends to the position below normal, the rod 45 is moved to the right, engaging the lever 46 with the pin 60, and moving the latter to the right, also moving the lever 55 to the left, or in the contra-clockwise direction. The effect of this movement will be to turn the ring 59 and lever 55, in a contra-clockwise direction. The movement of the rod 45 is slight, due to the difference in length of the levers 44 and 46, and to the releasing of the dog 38, which transfers the control to the crank lever 50. While the rod 45 is going to the right, the pitman 4 is also going to the right, and the lever 19, with pawl 20, and lever 50, is partaking of a contra-clockwise motion, the same as the ring 59 and lever 55. The roller 53 at the first part of this movement is traveling in the curved portion of the fixed cam 54, and is, therefore, being moved outward, away from the center of movement, namely,—the shaft 15. The result is, that the lever 50 will be oscillated upon its axis, and the notch 57 engaging with the projection 58 on the pawl 20, will lift the latter out of contact with the ratchet wheel 21. This condition will occur by the time the rod 45 reaches the extreme extent of its movement to the right. The further movement of the lever 19, in the contra-clockwise direction will continue to move the ring 59 in the same direction by the previously described engagement of the lever 50 with the notch 56, and the engagement of the notch 57 with the projection 58.

After the lever has moved to the extreme position in the contra-clockwise direction, it will then move through the arc in the clock-

wise direction. The pawl 20 will not then engage with the teeth of the ratchet 21, because it will be held out of engagement by the projection 58 being lifted by the corresponding lifting of the notch 57, of the lever 55, caused by the depression of the notch 56, in turn caused by the corresponding depression of the end of the lever 50, which, in turn, is caused by the elevation of the roller 53 in the raised portion of the cam 54. The shaft 15 will not be rotated during this reciprocation of the pitman 4, and consequently the board will not be lowered. When the roller 53 enters the lower or non-concentric part of the cam 54, the lever 50 will be turned upon its axis, lifting the free end of this lever out of contact with the notch 56 and allowing the notched end 55 to be depressed by the projection 58, caused by the expansion of the spring 51, the parts assuming the original position. Should the rod 45 be again moved to the right, caused by the finger 22 being in the position below normal, the same effect will result, namely,—

25 the pawl 20 will be lifted clear of the notches on the ratchet wheel, and consequently, the feeding devices will be disconnected. This action will continue until the pile of sheets is raised to such a height that the finger 22

30 when it descends will be arrested at the normal position, then the rod 45 will not be moved to the right, the lever 46 will not be swung, and the ring 59 will not be turned in the contra-clockwise direction. The lever 35 19, pawl 20, and lever 50 will be turned in the contra-clockwise direction as before, but the lever 55 not being moved, the free end of the lever 50, when depressed by the engagement of the roller 53 by the cam 54, will

40 swing beyond the end of the notch 56, and hence will not come into contact with the lever 55, and, therefore, the notch 57 will not be raised, and no interference will be had with the projection 58 and pawl 20. The

45 projection 58 will simply slide upon the curved concentric surface of the lever 55, and when it moves in the clockwise direction, the pawl 20 will be free to engage with the next tooth of the ratchet wheel 21.

50 It, therefore, appears that the feeding effect is intermittent and interrupted. It is merely essential that the feed be fast enough so that its maximum, when not disconnected, will exceed the growing effect of the pile. In other words,—the board should descend at a faster rate than the growth of the height of the pile, under the maximum circumstances. The feeding mechanism should, therefore, be adjusted to accommodate sheets of the maximum thickness.

55 When sheets of the maximum thickness are employed, the height of the pile, and the level of its top will gradually and slowly lower, causing the actuation of the disconnecting mechanism only at comparatively

infrequent intervals. The machine may then be used, without changing the adjustment, with sheets of the minimum thickness. The effect of this will be that the disconnecting mechanism will be brought into operation much more frequently. As an example, with very thick sheets, and assuming that the finger 22 is raised at intervals of four sheets fed to the board, then the raising of the level of the top of the pile, 75 by the accumulation of sheets being almost as fast as the downward feeding of the board, the disconnecting mechanism will operate only when, for example, ten sets of four sheets are fed, this number, 80 for example, being sufficient to raise the finger 22 from the position below normal to the normal position, and thus operate the disconnecting mechanism. When, for example, very thin sheets are fed, it might be 85 that after four sheets are fed, the board will be so low, and consequently, the top of the pile so low, that the finger will then be below normal, thus operating the disconnecting mechanism, and this operation will 90 continue for some time, so that, for example, the disconnecting mechanism will be operated when eight, when twelve, when sixteen, when twenty-four sheets or more are fed, before the top of the pile will 95 arrest the finger at the normal position, and, therefore, fail to operate the disconnecting device. In other words, the parts should be so proportioned that the board will be fed downward faster than the growth of the pile, under any circumstances, so that if the disconnecting mechanism were not present, the top of the pile would be lowered through 100 space. The disconnecting mechanism keeps the top of the pile from being lowered 105 through space more than the feeding movement of the board caused by the engagement of the pawl 20 with a single tooth of the ratchet wheel 21, which will be an inconsiderable trifle. In other words,—the top of 110 the pile will be kept at a practically uniform height in space, and the feeding devices will always act uniformly.

Another portion of the invention resides in the means whereby the board may be quickly raised in position to receive a new pile. This mechanism is best illustrated in Figs. 4 and 5. The nuts 10 and the shafts 11 are peculiar. Each nut is made in separate parts, and the threads of the shaft are 115 of the type known as ratchet threads, as shown, the top edge of the thread being substantially horizontal, and the bottom edge inclined. Each nut 10 comprises a casing 61 (see Fig. 5) having four chambers. In 120 each chamber is a block 62, with a threaded edge engaging with the shaft, and an opposite edge inclined and engaging with a similarly inclined edge of the casing 61. A spring 63 engages with each block 62, and 125

keeps it normally elevated, so that it is in contact with the casing 61, and shaft 11. These parts constitute a nut of such character that when the shaft 11 is rotated in the proper direction, the nut will be lowered, or raised, as depends upon the direction of rotation. When the operator desires to raise the board to its initial position for receipt of a new pile of sheets, he simply grasps 10 the frame 7, and raises it, the blocks 62 sliding by the ratchet threads on the shaft, and compressing the springs 63. The frame may, therefore, be very quickly raised to the initial position. For the purpose of allowing adjustment of the frame downward 15 or upward, without utilizing the previously described mechanism, I utilize a chain 64 (see Fig. 1) which is operated by a crank 65, and rotates a sprocket wheel 66 (see 20 Figs. 2 and 7). The operator can disconnect the pawl 20 from the ratchet wheel 21 by hand. The usual sheet guides 68 (see Fig. 3) are provided, and guide the sheets from the delivery mechanism to the pile.

25 It is to be understood that the finger 22 is best located in such a position that it will engage with the narrowest sheets that are utilized. In Fig. 2 it is shown as at about the middle of the board, but it may advantageously be placed to the extreme front of 30 the machine, so that it will always engage with the sheets, no matter how narrow they may be.

In accordance with the provisions of the 35 patent statutes, I have described the principle of my invention, together with the apparatus which I now consider to represent the best embodiment thereof; but I desire to have it understood that the apparatus shown 40 is merely illustrative, and that the invention may be carried out in other ways.

Having now described my invention, what I claim as new and desire to secure by Letters Patent, is:

45 1. A sheet piler comprising a board; means for feeding the latter; means for feeding sheets to the board; means acting in time with the sheet feeding means; a finger, connections, including a Geneva stop motion, 50 between the finger and the said last named means for moving the finger into contact with the pile and out of contact therewith during an interval between which separate sheets are fed to the board; and disconnecting mechanism, connecting the finger with the board feeding means, for actuating the latter.

55 2. A sheet piler, having in combination with a board, of rotary screw-threaded 60 shafts associated therewith; means for rotating the shafts; a nut on each shaft; a triangular projection on each nut; and connections between the projection and the board for supporting the latter.

65 3. A sheet piler having a board, and means

for delivering sheets thereto, means for feeding the board at a rate faster than the growth in height of the pile of sheets, a member engaging the top sheet of the pile at intervals, a shaft supporting the member, 70 connections between the member and shaft, and means controlled by the height of the pile for dislocating the connecting means.

4. A sheet piler having a board, and means for delivering sheets thereto, means for feeding the board at a rate faster than the growth in height of the pile of sheets, a member engaging the top sheet of the pile at intervals, an oscillating shaft supporting 80 the member, connections between the member and shaft, and means controlled by the height of the pile for dislocating the connecting means.

5. A sheet piler having a board, and means for delivering sheets thereto, means for feeding the board at a rate faster than the growth in height of the pile of sheets, a member engaging the top sheet of the pile at intervals, an oscillating shaft supporting the member, a lever secured to the shaft, a 90 flexible connection between the member and the lever, and means controlled by the movement of the member, for dislocating the connection.

6. A sheet piler having a board, and means for delivering sheets thereto, means for feeding the board at a rate faster than the growth in height of the pile of sheets, a member engaging the top sheet of the pile at intervals, an oscillating shaft supporting 100 the member, a device concentric with the shaft and movable relatively thereto, and means for transmitting the movements of the shaft to the device.

7. A sheet piler having a board, and means for delivering sheets thereto, means for feeding the board at a rate faster than the growth in height of the pile of sheets, a member engaging the top sheet of the pile at intervals, an oscillating shaft supporting 110 the member, a device concentric with the shaft and movable relatively thereto, means for transmitting the movements of the shaft to the device, and means for dislocating the transmitting means.

8. A sheet piler having a board, and means for delivering sheets thereto, means for feeding the board at a rate faster than the growth in height of the pile of sheets, a member engaging the top sheet of the pile at 120 intervals, an oscillating shaft supporting the member, a device concentric with the shaft and movable relatively thereto, means controlled by the engagement of the member with the pile of sheets for transmitting the 125 movements of the shaft to the device, and means for dislocating the transmitting means.

9. A sheet piler having a board, and means for delivering sheets thereto, means 130

for feeding the board at a rate faster than the growth in height of the pile of sheets, a member engaging the top sheet of the pile at intervals, an oscillating shaft supporting the member, a device concentric with the shaft and movable relatively thereto, means for transmitting the movements of the shaft to the device, and connections between the device and the feeding means.

10. A sheet piler having a board, and means for delivering sheets thereto, means for feeding the board at a rate faster than the growth in height of the pile of sheets, a member engaging the top sheet of the pile at intervals, an oscillating shaft supporting the member, a device concentric with the shaft and movable relatively thereto, means for transmitting the movements of the shaft to the device, means for dislocating the transmitting means, and connections between the device and the feeding means.

11. A sheet piler having a board, and means for delivering sheets thereto, means for feeding the board at a rate faster than the growth in height of the pile of sheets, a member engaging the top sheet of the pile at intervals, an oscillating shaft supporting the member, a device concentric with the shaft and movable relatively thereto, means controlled by the engagement of the member with the pile of sheets for transmitting the movements of the shaft to the device, means for dislocating the transmitting means, and connections between the device and the feeding means.

This specification signed and witnessed this sixth day of July, 1915.
